UNITED STATES PATENT OFFICE.

MAX OTTO CLAUSS, OF NEW YORK, N. Y., ASSIGNOR TO THE CLARK THREAD COMPANY, OF NEWARK, NEW JERSEY, A CORPORATION OF NEW JERSEY.

SKEIN HOLDER.

Application filed March 13, 1925. Serial No. 15,209.

To all whom it may concern:

Be it known that I, MAX OTTO CLAUSS, a citizen of the United States, residing in New York city, in the county of New York, 5 in the State of New York, have invented certain new and useful Improvements in Skein Holders, of which the following is a specification.

The invention relates to an improvement 10 in skein holders for winding machines and the like.

The object of the invention is to produce an improved and simplified skein holder of the type having two thread supporting 15 fingers spaced apart from each other with provision whereby a tubular band or holder may be slipped onto the skein on the completion of the winding operation while the skein still remains in the skein holder. To 20 this end the invention consists in the skein holder hereinafter described and particularly pointed out in the appended claims.

In the accompanying drawings illustrating the preferred form of the invention, 25 Fig. 1 is a side elevation of the improved skein holder, showing its relation to the operating parts of a winding machine; Fig. 2 is a front elevation of the parts shown in Fig. 1, with the thread spool omitted; and 30 Fig. 3 is a side elevation of the skein holder showing the completed and labeled skein and indicating the method of removing the skein from the holder.

The improved skein holder, as illustrated 35 in the drawings, comprises two thread supporting fingers 5 and 6 which are held spaced apart in fixed relation with each other for supporting the thread loops during the skein winding operation. The lower 40 finger 6 (as shown in the drawing) is hook-shaped to prevent the threads from spreading laterally during the winding. The upper finger 5 may be flat or curved to permit of the ready disengagement of the 45 thread loops therefrom on completion of the winding operation. To hold the loose end 7 for the formation of the first loop a slit 8 is provided in the finger 5. To keep the threads more or less confined to one spot the finger 5 is provided with a shoulder 9. As shown in the drawings the finger 5 projects laterally from the upper end of an upright 10 rising from the base 11, which also serves to support the finger 6. It 55 will be understood that this construction is

optional and that the fingers 5 and 6 may be supported in any preferred manner.

In order that a tubular band or label may be slipped longitudinally onto the skein threads while the skein still remains in the 60 holder on the completion of the winding operation, as shown in Fig. 3, the finger 6 is provided with a shank 12 for loosely supporting the label or band 13 during the winding operation. Before the winding 65 operation is commenced the tubular label or band 13 is placed on the shank or support 12, then when the skein is completed it is moved longitudinally along the support 12 and onto the skein threads as far as 70 the middle of the skein, as shown in Fig. 3. Upon the completion of the winding operation the thread leading to the thread supply is severed opposite substantially the middle of the skein and this loose end is 75 held in place by the tubular label or band. The loose end 7 is then disengaged from the slit 8 and the thread loops at this end of the skein are moved laterally along the 80 finger 5 to disengage the skein from the holder.

The skein winding operation may be accomplished by feeding the thread through a fixed thread eye and arranging the skein 85 holder so that it will rotate in such manner that the fingers 5 and 6 will travel in substantially the same circuit. It is preferred, however, to hold the thread supporting fingers 5 and 6 stationary and to loop the thread about them. This is the 90 mode of operation illustrated in the drawings. The thread delivering eye 15 is supported on the laterally extending end 16 of an arm 17 mounted on a shaft 18 (which is located substantially halfway between 95 the fingers 5 and 6) journaled in the upper end of an upright 19, the lower part of which is not indicated. The shaft 18 is provided with a pulley 20 around which passes a belt 21 driven from a source of power not 100 shown in the drawings.

The thread 24 is supplied from a cone 25 mounted loosely on the upright pin 26. The thread 24 passes through the hollow axis of the shaft 18 and thence through a hole 27 105 in the end 16 of the arm 17 to the delivering eye 15. When the loose end 7 of the thread is caught in the slit 8 and the shaft 18 is actuated the thread is looped about the fingers 5 and 6 to form a skein consisting of 110

longitudinally extending superimposed loops. When the completed and labeled skein is removed from the skein holder, the loose thread end 7 serves to indicate to the user what end to pull to unwind the skein without entanglement while enclosed in its band.

Having thus described the invention what I claim as new is:—

- 10 1. A skein holder for winding machines comprising, two thread supporting fingers spaced apart, each finger being adapted to receive and hold the opposite ends of the loops constituting the skein, one of said fingers being provided with a shank for holding a tubular band to be slipped over the finger and onto the skein threads on the completion of the winding operation.
- 15 2. A skein holder for winding machines

comprising, two thread supporting fingers 20 spaced apart in fixed relation, one finger being in the form of a hook and the other finger being formed to permit of the lateral displacement of the skein therefrom.

3. A skein holder for winding machines 25 comprising, two fingers spaced apart in fixed relation to support the thread loops during the winding operation, one of said fingers being shaped to permit of the lateral displacement of the loop threads therefrom and the other of said fingers being hook-shaped and having a shank for holding a tubular band during the winding operation to permit the band to be slipped onto the skein threads while the skein still remains in the holder on the completion of the winding operation.

MAX OTTO CLAUSS.
